UNITED STATES PATENT OFFICE

2,334,208

PLURAL POWER OPERATED MECHANISM

Horace N. Lee, New York, N. Y., assignor to Sullivan Machinery Company, a corporation of Massachusetts

Application October 28, 1941, Serial No. 416,922

3 Claims. (Cl. 254—187)

My invention relates to power driven apparatus of the type in which a plurality of power operated mechanisms may be caused to perform selectively or simultaneously their working functions by power from a prime mover. It relates more particularly to combined pumping and hoisting mechanisms driven by a common source of power and having improved means for selectively or simultaneously controlling the pumping of fluid by the pumping mechanism and the doing of work by the hoist.

It is sometimes necessary to have for certain types of construction work, a source of compressed air for pneumatic tools and a hoist for moving or lifting materials. At times it may only be necessary to deliver compressed air from its source, while at other times only the hoist may be needed. There are times, however, when a supply of compressed air is needed and it is also desirable to use the hoist for lifting light loads. In a co-pending application by Ralph E. Lamberton, Serial No. 379,943, filed February 21, 1941, there is shown a compressor and a hoist arranged to be driven directly by a single prime mover, and having means for controlling selectively the pumping of fluid by the compressor and the doing of work by the hoist. The arrangement shown in this application is to an extent similar to that of the Lamberton application, but I have provided control mechanism whereby the compressor and hoist may be caused to function either selectively or simultaneously. It will be understood that power operated devices other than a hoist may be used with the compressor, and that the compressor is merely illustrative of the various pumping devices that may be used.

It is an object of my invention to provide an improved apparatus in which a pumping device and a separate power driven mechanism may be caused to perform selectively or simultaneously their working functions by power from a single power unit. Another object of my invention is to provide, for a combined pumping apparatus and hoisting mechanism, improved means for controlling the driving of the hoisting mechanism and the operation of the pumping apparatus. Still another object is to provide a compressor connected continuously in driven relation with a power unit, pressure responsive means for controlling the unloading of the compressor and the supply of operating fluid to the power unit, and a hoisting mechanism having improved means for connecting it in driven relation with the power unit and rendering the pressure responsive means controlling the supply of operating fluid to the

power unit ineffective. Another object is to provide improved means for controlling the driving of a pumping apparatus and a separate power driven mechanism from a single power unit, and having improved means for controlling the speed of the power unit. Other objects and advantages will appear in the course of the following description.

In the accompanying drawings there is shown for purposes of illustration one form which my invention may assume in practice.

In these drawings:

Fig. 1 is a side elevational view with parts broken away showing an illustrative form of the invention.

Fig. 2 is a plan view, with parts broken away, of the mechanism shown in Fig. 1.

Fig. 3 is an enlarged sectional view through a compressor cylinder, taken on a plane including the axis of the cylinder.

Fig. 4 is an enlarged vertical sectional view through a valve for controlling the supply of operating fluid to compressor unloading means, the section being taken on line 4—4 of Fig. 2.

Fig. 5 is a view similar to Fig. 4, showing the valve in a different position.

Fig. 6 is an enlarged vertical sectional view through a valve for controlling the flow of pressure fluid to the control device for the engine throttle, and is taken on line 6—6 of Fig. 2.

Fig. 7 is a view similar to Fig. 6, but showing the valve in a different position.

In the illustrative embodiment of the invention there is shown a base structure 1 which is adapted for sliding over the ground and which has mounted thereon a power unit 2, a pumping apparatus 3 in the form of a compressor, and a power driven device 4 shown herein in the form of a hoist. Surrounding the power unit and the compressor is a casing 5.

The power unit may assume various forms but is shown herein as an engine of the internal combustion type arranged with its power shaft extending longitudinally of the base structure. A radiator 7 is mounted on the end of the base structure adjacent the engine and contains cooling fluid for the latter. At the side of the engine is a throttle device 8 which is controlled by manually operated and automatically operated means, generally designated 9, which will be described shortly more in detail.

The compressor 3 shown herein is of the multi-cylinder, single stage type having cylinders 11 and 12 extending radially from a crankcase 13; and the compressor crankshaft, a portion of which is

shown at 14, is arranged in alignment with the power shaft of the engine and is driven directly thereby. The crankshaft may, of course, be driven by the power shaft through a clutch or any other suitable means. A fan 15 is mounted on a bracket 16 connected to the compressor crankcase, and is driven by a belt 17 engaging a pulley 18 on the crankshaft for circulating cooling air through the casing 5 about the compressor and the engine.

The compressor cylinders are identical in construction, and each comprises, as shown in Fig. 3, a cylinder member 20 having a bore 21 within which a piston 22 is reciprocated by the compressor crankshaft through a connection not shown. A valve mechanism generally designated 23 and a cylinder head 24 are arranged in an enlarged bore 25 formed in the cylinder member, and the cylinder head is secured as by bolts 26 to the cylinder member in engagement with the valve mechanism for clamping the latter against a shoulder 27 at the junction of the bores 21 and 25. Connected to the side of the cylinder member as by bolts 28 is a conduit 29 having an air filter 30 attached to its outer end and opening at its inner end into an intake passage 31 which communicates with the cylinder bore 21 past an inlet valve 32. A discharge valve 33 controls the flow of compressed air from the cylinder to a passage 34 leading to a discharge conduit 35. The discharge conduits from the cylinders 11 and 12 are connected to a common conduit 36 which delivers the compressed air to a storage tank or receiver 37 supported above the base structure by support members 38 and 39.

An unloading device generally designated 40 is provided for each of the compressor cylinders. This unloading device includes members 41 and 42 and a plate 43 attached to the top of the cylinder head by bolts 44. Formed between the members 41 and 42 is a chamber 45, and a flexible diaphragm 46 is clamped in the chamber 45 between the members 41 and 42. A plunger 48 is provided with a reduced portion 49 projecting into the chamber 45 through an opening in the plate 43, and with an enlarged portion 50 which is received within a recess 51 formed in the upper surface of the cylinder head. Rods or fingers 52 are attached to the enlarged portion 50 of the plunger and project downwardly through openings 54 in the cylinder head into the intake passage 31, and are engageable at their lower ends with the inlet valve to move the latter from its seat and unload the compressor cylinder when the plunger is forced downwardly. The plunger is normally held in its upper position against the diaphragm by a spring 55 shown herein as being of the bowed plate type. The spring 55 and the plunger are guided by a pin 56 fixed to the cylinder head and projecting upwardly through an opening in the spring and into a recess 57 formed in the plunger. Surrounding the reduced portion of the plunger just above the plate 43 is a packing ring 58 carrying a packing which sealingly engages the plunger to prevent the passage of pressure fluid from the chamber 45 to the recess 51. A coiled spring 59 rests upon the packing ring and acts against the lower surface of the diaphragm for holding the latter normally in its raised position.

The plunger 48 may be moved to its lower position to effect opening of the inlet valve and unloading of the compressor cylinder by admitting pressure fluid to the chamber 45 beneath the diaphragm so that it acts directly on top of the

plunger, or by admitting pressure fluid to the space above the diaphragm so that the diaphragm will be forced downwardly and move the plunger to its valve opening position. To effect automatic unloading of the compressor and reloading thereof in accordance with compressor discharge pressure variations, there are provided conduits 60 opening into the chambers 45 beneath the diaphragms 46 of the unloading devices, and these 10 conduits are connected to a common conduit 61 communicating through a standard device 62, which permits free flow of pressure fluid toward the unloading plungers but delays venting of fluid from these plungers, to a pilot valve 63, illustrated herein as a so-called RC pilot valve, connected in the compressor discharge conduit 36. The pilot valve is operative at a predetermined maximum compressor discharge pressure to supply fluid from the discharge line past the device 20 62 to the conduit 61, and, at a predetermined minimum discharge pressure, to vent the conduit 61.

At times it is desired to unload the compressor so that the engine may drive the hoist for lifting 25 heavy loads. In order that this may be accomplished even when the pressure in the receiver and the discharge line is atmospheric, there are provided conduits 65 opening into the chambers 45 above the diaphragms 46 of the unloading devices, and these conduits are connected to a common conduit 66 which opens into a valve casing 67, as shown in Figs. 4 and 5. Arranged in the crankcase of the compressor is a lubricant pump, not shown, for supplying lubricant to parts 30 of the compressor mechanism, and connected to this lubricant pump is a conduit 68 which opens into the valve casing 67. A conduit 69 connected to the valve casing leads to the compressor crankcase and is adapted to return oil to the latter. A 40 valve 70 is rotatably mounted in the valve casing and is provided with a groove 71 for connecting the conduits 66 and 68 when it is in one of its limiting positions, and for connecting conduits 66 and 69 when it is in another limiting position. 45 A manual control lever 73 is connected to the valve 70 for moving the latter to its different positions and controlling the flow of lubricant relative to the unloading devices. This is operator-controllable at will.

50 In order to drive the hoist, there is provided a coupling 75 connecting a shaft 76 to the rear end of the compressor crankshaft 14, and the shaft 76 is connectible through a clutch mechanism, generally designated 77, to a shaft 78. The clutch mechanism may be of any suitable 55 type but as shown herein is similar to that described in detail in the above mentioned application to Lamberton and so will not be described again here. An operating lever 79 is provided 60 for controlling the connection of the shafts 76 and 78 through the clutch mechanism and when the lever is moved in a clockwise direction to its extreme position the clutch is disconnected, while a connection is effected when the lever is moved 65 in a counterclockwise direction. Power is transmitted from the shaft 78, as shown in Fig. 2, through a flexible drive member 80, such as a belt or chain, to a shaft 81 which is connected through suitable gearing, not shown, to the drum 70 82 of the hoist 4. Suitable means are provided for controlling the operation of the drum and are shown here as including operating levers 84, 85 and 86. The lever 84 is connected through a link 87 to a shaft 88 which effects operation of 75 a clutch, not shown, controlling the drive of the

drum. The lever 86 is connected through a link 90 to a shaft 91 on which a dog 93 is fixed and is movable by the shaft 91 into engagement with teeth 94 on the drum for locking the latter against rotation in an unwinding direction. The lever 86 is connected through a link 95 to a shaft 96 and controls the operation of a brake, not shown, for braking the rotation of the drum.

Referring to the control means 8 for the throttle device 2 of the engine, it will be noted that a rod 98 is connected at one of its ends to the throttle and is connected at its other end to an arm 99 mounted for pivotal movement at 100. Suitable pressure responsive means 101 is provided for effecting a swinging of the arm 99 about its pivot to move the rod 98 in a direction to close the throttle valve when pressure fluid is supplied thereto. A conduit 103 leads from the device 62 at a point communicating freely with the delivery side of the pilot valve 63 (so that the device 62 will not affect flow of fluid in the conduit 103) and is connected through a control valve 104 to a conduit 105 leading to the pressure responsive means 101. A lever 107, pivotally mounted between its ends, operatively engages, at one of its ends, the rod 98, and is connected at its other end to a rod 108 which is connected to a lever 109 that may be manually operated to open or close the throttle. The control valve 104 may assume various forms but is shown in Figs. 6 and 7 as including a valve casing 110 having ports 111 and 112 with which the conduits 103 and 105 are connected through threaded connection elements 113 and 114. A valve element 115 is rotatably mounted within the casing 110 and is provided with a groove 116 for connecting the ports 111 and 112 when the valve is in one of its positions, and with a groove 117 for connecting the port 112 with a vent port 118 when the valve is rotated to another position. Connected to the valve, as shown in Fig. 1, is an arm 120 having its outer end yieldably connected through springs 121 and 122 to a rod 123 which is connected to the operating lever 79 for the clutch mechanism 71.

The operation of the mechanism described is as follows: Assuming that it is desired only to compress air for delivery to the receiver, the lever 79 will be swung into the position shown in Fig. 1 to disconnect the hoist drive shaft 78 from driving relation with the engine and to move the valve element 115 of the valve 104 into the position shown in Fig. 6 for connecting the conduits 103 and 105 in communication with each other through the groove 116. In order that the unloading devices for the compressor cylinders may assume their loading positions, fluid is vented from the spaces above the diaphragms 46 by turning the lever 73 into a position connecting the conduits 66 and 69 through the valve groove 71 and thereby venting fluid to the compressor crankcase. When the engine 2 is started, the compressor 3 is driven loaded until the pressure in the receiver has reached the value at which the pilot valve 63 operates to supply pressure fluid from the discharge line through the device 62 to the conduit 61 and the conduits 60 opening into the chambers 45 of the unloading devices below the diaphragms 46. Pressure fluid supplied to the chambers 45 acts on the upper ends of the plungers 48, forcing the latter toward their lower position and moving the fingers 52 against the inlet valves to force the latter from their seats and unload the compressor. Pressure fluid is supplied at the same time from

the pilot valve 63 independently of control by the device 62 to the conduit 103, and through the groove 116 in the valve element 115 to the conduit 105 which delivers the fluid to the pressure responsive means 101 for effecting actuation of the engine throttle toward its closed position. As long as the compressor discharge pressure remains at a value sufficient to hold the pilot valve open, the engine 2 operates at a reduced speed and drives the compressor unloaded. When pressure fluid is used from the receiver and the pressure in the discharge line drops, the pilot valve operates at a predetermined pressure, lower than that at which unloading occurred, to vent pressure fluid from the compressor unloading devices and from the pressure responsive device for the engine throttle. Due to the free communication between the conduit 103 and the pilot valve, independent of restriction by the device 62, fluid from the throttle control device will be vented immediately to atmosphere, but, since the device 62 provides a delayed venting of pressure fluid from the compressor unloading device, the compressor will be driven unloaded while the engine is picking up speed.

If it is desired to connect the hoist 4 in driven relation with the engine 2, the lever 79 is moved in a counterclockwise direction from its position shown in Fig. 1 to actuate the clutch for connecting the hoist drive shaft 78 in driving relation with the compressor crankshaft. At the same time, the valve element 115 of the valve 104 is moved by means of the rod 123 and springs 121, 122 to a position for venting pressure fluid from the throttle control device and for cutting off the supply of fluid from conduit 103. The engine throttle is then made responsive only to the manual control (except as other speed responsive controls may be provided) through the lever 109, the rod 108, the lever 107 and the rod 98, so that the engine may be caused to operate at any desired speed to carry the load of the compressor and the hoist. If the load of the hoist and the compressor is too large for the engine, the compressor may be unloaded by operating the lever 73 to move the valve 70 into a position for supplying oil under pressure from the compressor crankcase through the conduit 68, the groove 71 in the valve 70, the conduit 66 and the conduits 65 to the spaces above the diaphragm in the unloading device for forcing the diaphragm and the unloading plunger to their lowered unloading positions.

As a result of this invention, it will be noted that there is provided improved means for controlling the driving of a pumping apparatus and a separate power driven mechanism from a single power unit. It will further be noted that by reason of the improved control means, the pumping apparatus may be driven alone while the speed of the power unit is controlled by either automatic or manual control devices, and the separate power driven mechanism may be connected in driven relation with the power unit while the pumping apparatus operates either loaded or unloaded with the speed of the power unit controlled only by a manual control device.

While there is provided in this application one form which my invention may assume in practice, it will be understood that this form is shown for purposes of illustration and that the invention may be modified and embodied in various other forms without departing from its spirit or the scope of the appended claims.

What I claim as new and desire to secure by Letters Patent is:

1. In combination, a power unit, a compressor connected for drive by said power unit, a pressure responsive device for controlling the supply of operating fluid to said power unit, means operative at a predetermined discharge pressure of said compressor for supplying pressure fluid to said pressure responsive device, a power driven mechanism adapted to be driven by said power unit, means for controlling the connection of said power driven mechanism in driven relation with said power unit, valve means for controlling the supply of pressure fluid to said pressure responsive device, said valve means being operative to cut off the flow of pressure fluid to said pressure responsive device and to vent the latter completely to atmosphere, and means including a manually operated element common to both functions for controlling the operation of said valve means and said connection controlling means.

2. In combination, a power unit, a compressor connected for drive by said power unit, a pressure responsive device for controlling the supply of operating fluid to said power unit, means operative at a predetermined discharge pressure of said compressor for supplying pressure fluid to said pressure responsive device, a power driven mechanism adapted to be driven by said power unit, a clutch for controlling the connection of said power driven mechanism in driven relation with said power unit, a valve for controlling the supply of pressure fluid to said pressure responsive device, and means including a manually operated element for controlling the operation of said valve and said connection controlling means, said last mentioned means being arranged for effecting simultaneously an operation of said clutch for connecting said power driven mechanism in driven relation with said power unit and the closing of said valve.

3. In combination, a power unit, a pumping apparatus connected for drive by said power unit, pressure responsive unloading means for said pumping apparatus, a pressure responsive device for controlling the supply of operating fluid to said power unit, means operative at a predetermined discharge pressure of said pumping apparatus for supplying pressure fluid to said unloading means and to said pressure responsive device, a power driven mechanism adapted to be driven by said power unit, means for controlling the connection of said power driven mechanism in driven relation with said power unit, valve means for cutting off the supply of pressure fluid to said pressure responsive device and venting the latter to atmosphere, and manually operated means for controlling simultaneously the operation of said valve means and said connection controlling means.

4. In combination, a power unit, a pumping apparatus connected for drive by said power unit, pressure responsive unloading means for said pumping apparatus, a pressure responsive device for controlling the supply of operating fluid to said power unit, means operative at a predetermined discharge pressure of said pumping apparatus for supplying pressure fluid to said unloading means and to said pressure responsive device, a power driven mechanism adapted to be driven by said power unit, means for controlling the connection of said power driven mechanism in driven relation with said power unit, valve means for cutting off the supply of pressure fluid

to said pressure responsive device and venting the latter to atmosphere, manually operated means for controlling simultaneously the operation of said valve means and said connection controlling means, and manually operated means for controlling a supply of fluid under pressure to said unloading means.

5. In combination, a power unit, a compressor connected continuously in driving relation with said power unit, pressure responsive unloading means for said compressor, a pressure responsive device for controlling the supply of operating fluid to said power unit, means operative at a predetermined compressor discharge pressure for supplying pressure fluid to said unloading means and to said pressure responsive device, a hoist adapted to be driven by said power unit, a clutch for controlling the connection of said hoist in driven relation with said power unit, valve means for cutting off the supply of pressure fluid to said pressure responsive device and venting the latter to atmosphere, and manually operated means for controlling simultaneously the operation of said valve means and said connection controlling means.

6. In combination, a power unit, a compressor connected continuously in driving relation with said power unit, pressure responsive unloading means for said compressor, a pressure responsive device for controlling the supply of operating fluid to said power unit, means operative at a predetermined compressor discharge pressure for supplying pressure fluid to said unloading means and to said pressure responsive device, a hoist adapted to be driven by said power unit, a clutch for controlling the connection of said hoist in driven relation with said power unit, valve means for cutting off the supply of pressure fluid to said pressure responsive device and venting the latter to atmosphere, manually operated means for controlling simultaneously the operation of said valve means and said connection controlling means, and manually operated means for controlling a supply of fluid under pressure to said unloading means, said last mentioned means being operative at will for supplying fluid to said unloading means and effecting an unloading of said compressor.

7. In combination, a power unit, a pumping apparatus connected for drive by said power unit, a pressure responsive device for controlling the supply of operating fluid to said power unit, means including passage means for supplying pressure fluid to said pressure responsive device, valve means arranged in said passage means for cutting off the supply of pressure fluid to said pressure responsive device and venting the latter to atmosphere, a power driven mechanism adapted to be driven by said power unit, means for controlling the connection of said power driven mechanism in driven relation with said power unit, and manually operated means for effecting simultaneous operation of said valve means and said connection controlling means, said last mentioned means being operative to effect a venting of said pressure responsive device when said power driven mechanism is connected for drive by said power unit.

8. In combination, a power unit, a pumping apparatus connected for drive by said power unit, a pressure responsive device for controlling the supply of operating fluid to said power unit and operative on the supply of pressure fluid thereto for reducing the supply of operating fluid, means responsive to pump discharge pressure for supply-

ing pressure fluid to said pressure responsive device, valve means for cutting off the supply of pressure fluid to said pressure responsive device and venting the latter to atmosphere, a power driven mechanism adapted to be driven by said power unit, means for controlling the connection of said power driven mechanism in driven relation with said power unit, and means including a

manually operated element for controlling the operation of said valve means and said connection controlling means, said last mentioned means being operative to effect a venting of said pressure responsive device when said power driven mechanism is connected for drive by said power unit.

HORACE N. LEE.
